UNITED STATES PATENT OFFICE

95,585

DESIGN FOR A COMBINED CONTROLLING AND INDICATING DEVICE FOR RADIOPHORE- CEIVERS

Emil Harman, Philadelphia, Pa., assignor to
Philco Radio & Television Corporation, Phila-
delphia, Pa., a corporation of Delaware

Application February 27, 1935, Serial No. 55,646

Term of patent 14 years

To all whom it may concern:

Be it known that I, Emil Harman, a citizen of the United States, residing in Philadelphia, Pennsylvania, have invented a new, original, and ornamental Design for Combined Controlling and Indicating Device for Radio Receivers, of which the following is a specification, reference being had to the accompanying drawing, forming part thereof, in which:

Figure 1 is a face view of a combined controlling and indicating device for radio receivers illustrating my new design; and

Fig. 2 is a side elevation.

I claim:

The ornamental design for a combined controlling and indicating device for radio receivers, substantially as shown.

EMIL HARMAN.
